UNITED STATES PATENT OFFICE.

FLORENCE A. THOMSON, OF PHILADELPHIA, PENNSYLVANIA.

DESIGN FOR A CANDY BOX.

Application filed November 15, 1926. Serial No. 19,733. Term of patent 7 years.

To all whom it may concern:

Be it known that I, FLORENCE A. THOMSON, a citizen of the United States, residing at Philadelphia, in the county of Philadelphia, and State of Pennsylvania, have invented a new, original, and ornamental Design for Candy Boxes, of which the following is a specification, reference being had to the accompanying drawings, forming part thereof.

Figure 1 is a perspective view of a candy box embodying my design;

Fig. 2 is a side elevation thereof;

Fig. 3 is a side elevation of the other side thereof.

What I claim as new and desire to secure by Letters Patent, is:

The ornamental design for a candy box as shown.

In testimony whereof, I have hereunto signed my name.

FLORENCE A. THOMSON.
